F. P. MANSBENDEL,
TELEPHONE APPARATUS,
APPLICATION FILED JUNE 13, 1917.

1,399,268.

Patented Dec. 6, 1921.

Fritz P. Mansbendel Inventor
By his attorney, Felt & Schuck

UNITED STATES PATENT OFFICE.

FRITZ P. MANSBENDEL, OF BROOKLYN, NEW YORK, ASSIGNOR TO ULTRA EARPHONE CO., INC., OF NEW YORK, N. Y., A CORPORATION OF NEW YORK.

TELEPHONE APPARATUS.

1,399,268.

Specification of Letters Patent. Patented Dec. 6, 1921.

Application filed June 13, 1917. Serial No. 174,481.

To all whom it may concern:

Be it known that I, FRITZ P. MANSBENDEL, a citizen of the German Empire, and who have declared my intention of becoming a 5 citizen of the United States, and a resident of Brooklyn, in the county of Kings and State of New York, have invented certain new and useful Improvements in Telephone Apparatus, of which the following is a specification.

The invention relates to telephone receivers or transmitters, more particularly to portable apparatus such as is intended for use by deaf persons or with loud talking 15 apparatus, and designed to be more sensitive than the type of receiver or transmitter in general use.

The invention has for its object to provide a rigid and substantial construction, consisting of few and simple parts; and wherein the tension placed upon the armature may be readily controlled or adjusted. A further object of the invention is to provide a convenient means of securing the conductors to 25 the receiver terminals and of affording suitable protection therefor.

The nature of the invention will be best understood when described in connection with the accompanying drawings, in which—
30 Figure 1 is a plan of the instrument with cap removed.

Fig. 2 is a vertical section therethrough, taken on the line 2—2, Fig. 1.

Fig. 3 is a plan of the back of the instrument and shows the manner of connecting the conductors to the instrument terminals.

Fig. 4 is a similar view with the protecting cap for the conductors attached.

Similar characters of reference designate 40 corresponding parts throughout the several views.

Referring to the drawings, 10 designates a suitable casing within which is mounted, in any convenient manner, a permanent 45 magnet 11 having poles 12 and provided with energizing windings or telephone current coils 13. The coils 13 are connected through conductors 14 with terminal rods 15 extending through the back of the casing 50 10 and insulated therefrom, said rods terminating in conical tips 16 for outside connection. The tips 16 are preferably slightly concaved and are adapted to receive eyes 17 at the ends of a pair of flexible conductors 55 18. In order to insure a good contact be-

tween a tip 16 and a conductor 17, as well as to protect the connection against corrosion and external injury, a cap 19 of insulating material is designed to fit over the same and is attached to the casing wall by means of a 60 screw 20 which passes through the cap and the said casing wall and is held in a nut 21 within the casing. The said cap 19 is recessed sufficiently to permit its base to fit upon the back of the casing 10, and at the same 65 time to press the eyes over the tips to insure a good contact and to seal the connection. The conductors 18 are brought out through a suitable outlet 22 cut into the under face of the cap 19, the entire attachment thus 70 presenting a smooth and finished appearance and affording a dust-proof cover for the conductor ends which are firmly clamped upon and spread over the tips 16. A positive contact is thereby insured without in any way 75 disturbing the internal circuit; and the said conductors, furthermore, may readily and conveniently be detached from the instrument.

In front of the pole pieces 12 is pivotally 80 secured an armature piece 25, the same being located, for example, in a plane substantially at right angles to the diaphragm 26 of the receiver, and the said piece is integral with or rigidly attached to one end of an arm 27 85 whose other and rounded end 28 bears against the said diaphragm 26. The lever thus formed may be pivoted or fulcrumed in any convenient manner to the casing 10; and is herein disclosed as attached to a flexible strip 29 whose ends are screwed to posts 90 30 extending upwardly from the bottom of the casing.

The diaphragm 26 is mounted in and carried by a cap 31 which is internally threaded to be screwed down over the top of the casing 10 correspondingly threaded. The mounting of the said diaphragm in the cap may be effected in any well-known or special manner to hold it at the circumference 100 to the cap and preferably near the outer wall thereof, as, for example, by means of a suitable clamping ring 33 whereby the said cap and diaphragm become so united as to be movable as one member. The said cap, also, is provided with a central opening 32 through which the sound waves are emitted or received.

The end 28 of the lever arm 27, as aforesaid, bears upon the diaphragm; and, by 110

turning the cap 31 on the casing 10, the other end of armature 25 of said lever may be located at the particular distance from the co-operating pole pieces 12, where the magnetic attraction on armature 25 is balanced by the deflection of diaphragm 26. In this manner, the particular tension under which the said armature is maintained, under the action of the magnets 11, may be 10 adjusted to the desired degree. When the proper position has been attained, the cap may be locked to the casing in manner well understood to prevent tampering with the adjustment. It will be noted that the end 15 of the lever 27 is not directly attached to the diaphragm, although it is in intimate contact therewith, and all movements of the said diaphragm are transmitted to the armature and vice versa. It has been found 20 that an instrument thus constructed affords a very efficient receiver, or transmitter, for the sound waves and reproduces the same with great fidelity. The free connection between diaphragm 26 and the lever 27 eliminates all securing elements and the localization of mass in the center of the dia- 25 phragm, which tends to damp or change the natural periodicity of vibration of the diaphragm, and dispenses with any dis- torting stresses always present in a rigid connection. Furthermore, slight irregularities in the manufacture of the casing parts will be readily accommodated, the lever end assuming a natural position relative to the diaphragm at or near the center thereof. 35

I claim:

A telephone instrument, comprising: a casing; a cap rotatable thereon; a diaphragm retained in said cap; a permanent magnet mounted in said casing, having pole 40 pieces toward and away from which the said diaphragm is movable through rotation of the said cap; and a winding for said magnet; a lever mounted in said casing; and a flexible strip connected to said lever 45 and to said casing for fulcruming the former on the latter, said lever having at one end an armature in proximity to the poles of said magnet and influenced thereby, and having its other end engaging said dia- 50 phragm but being unattached thereto.

Signed at New York, in the county of New York and State of New York, this 11th day of June, A. D. 1917.

FRITZ P. MANSBENDEL.

Witness:

Laura E. Smith.
